(57) **CLAIM**

The ornamental design for a cleaning tool, as shown and described.

DESCRIPTION

FIG. 1 is perspective view of a first embodiment of cleaning tool incorporating our new design, viewed from in front of, above, and from the left side of the cleaning tool;

FIG. 2 is a left-side elevation view thereof, with the right side being a mirror image of the left side;

FIG. 3 is a top plan view thereof;

FIG. 4 is a front elevation view thereof;

FIG. 5 is a rear elevation view thereof; and,

FIG. 6 is a bottom plan view thereof.

The broken lines showing of the interior structure, prongs, and various regions are included for the purpose of illustrating unclaimed portions and form no part of the claimed design.

1 Claim, 2 Drawing Sheets
